UNITED STATES PATENT OFFICE.

CARL AUGUST JOHANSON, OF DULUTH, MINNESOTA.

GRAIN-CAR DOOR.

Application filed March 29, 1926. Serial No. 98,274.

The invention aims to provide a new and improved grain car door, which will be rather simple and inexpensive, yet will be practicable and in every way desirable.

5 The door is mounted for swinging either to a closed horizontal position or to a vertical open position, and a further object of the invention is to provide unique means for holding said door in either of these positions.

Another object is to provide novel means for holding the door in any partly open position which may be desired, said means forming part of a brake structure, by means 15 of which the lowering of the door to closed position, may be controlled.

With the foregoing and minor objects in view, the invention resides in the novel subject matter hereinafter described and 20 claimed, the description being supplemented by the accompanying drawings.

Figure 1 is a perspective view showing the door in closed position in full lines but in dotted lines illustrating one way in which 25 it may be held in open position.

Figure 2 is a perspective view illustrating the preferred manner of holding the door in open position.

Figure 3 is an outer side elevation.

30 Figure 4 is an inner side elevation illustrating more particularly the action of the brake for controlling the lowering of the door.

In the drawings above briefly described, 35 numerals 5 and 6 designate the stiles of a car door frame, 7 designates a door for the lower portion of said frame, and 8 designates an initial discharge door for an opening 9 in the door 7.

40 The door 7 is preferably formed from a single metal plate reenforced by an angle metal bar 10 riveted to it, or by a number of such bars, one end of this door being provided with a bolt 11 to engage a keeper in the stile 5, when the door is closed. In addition to this securing means, the upper corner portions of the door 7 are preferably provided with studs 12 for reception in

45 sockets in the inner sides of the stiles 5 and 6, said studs serving to hold the door against end-wise creeping and outward falling, even though it should break loose from the remainder of its mounting means, hereinafter described. Suitable handles 13 50 are of course provided on the door to assist in opening and closing the same.

The door 8 is hinged at 14 to the door 7, and by means of any desired fasteners 15, may be locked in closed position. Another fastener 16 is preferably provided at the 60 lower edge of the door 8 to engage a keeper 17 on the door sill. All of these latches or fasteners are preferably provided with safety dogs 18 for effectively holding them in locked position. When the latches are released, the door 8 may be swung outwardly and upwardly and then supported by hook 19 on the door 7, said hook being engaged with an opening 20 in the latch 16, in the 65 present disclosure.

70 One lower corner of the door 7 is hinged-ly mounted as at 21, at the lower end of the stile 6, the hinge including a horizontal pivot 22 and a vertical pivot 23. The door 7 may be horizontally swung about the vertical pivot 3, against the inner side of the car, as shown in dotted lines in Figure 1, and it may be held in this position by means which will hereinafter be described. Upon the horizontal pivot 22 however, the 80 door may be swung to its preferred open position, as disclosed in Figure 2. Novel provision is made for holding this door either in closed position or in the open position last referred to. This means includes 85 a door-holding member 24 which is engage-able with the upper edge of the door, whether the latter be closed as in Figure 1, or open as in Figure 2, and a vertical guideway is provided for said holding 90 member, permitting it to move to either of its operative positions. In the preferred construction, the holder 24 is in the form of a bifurcated arm projecting laterally and downwardly from a vertically disposed 95 sleeve 25, said sleeve slidably surrounding a verticle rod 26 whose ends are laterally directed and secured at 26' to the stile 6.

100 When the holding member 24 is engaged with the door 7, in either position of the lat-ter, it holds it against inward swinging away from the car 9, and it will be clear from the drawings that this member may slide along the rod 26 when it is to be released or applied, or moved to either posi-tion at which it is needed.

105 Mounted at the inner side of the car and preferably joined integrally to the rod 26 near one of its ends, is an inclined brake rod or track 27, one end 28 of this rod or track being laterally directed and secured to the stile 6, while its lower or other end is 110

bent to provide a hook 29, the rod or track being anchored to the car side adjacent this hook, by any suitable means 30. When the door 7 is swung to the open position shown in Figure 2, the hook 29 receives it and cooperates with the member 24 in holding it in open position.

A brake lever 31 is connected with the door 7 by a chain 32 and is provided with 10 a guide 33 which under ordinary circumstances may loosely slide along the rod 27, but when the lever is angled as shown in Figure 4, said guide will frictionally engage the aforesaid rod, so that an effective brake 15 is provided for controlling the lowering of the door 7, as illustrated in Figure 4. Near the upper end of the chain 32, hook 34 is preferably provided, and by engaging a portion of said chain with said hook, 20 after door 7 has been upwardly swung to any desired inclined position, said door may be held in such position. The chain and hook are also instrumental in supporting the door 7 when it is horizontally swung 25 inwardly against the side of the car and is lifted somewhat as disclosed in dotted lines in Figure 1.

By employing the novel construction shown and described or a substantial equivalent thereof, a grain car door is produced 30 which is extremely simple and inexpensive, yet is practical, durable and in every way desirable. On account of these existing advantages, details shown are preferably followed. However, within the scope of the 35 invention as claimed, variations may of course be made.

I claim:

1. A locking means for a door pivoted 40 near one vertical edge for upward swinging to open position, said means comprising a holding member for engagement with the upper edge of the door when the latter is in either its closed or open position, and 45 a stationary vertical guideway along which said holding member is slidable to either of its operative positions.

2. A holding means for a door pivoted near one vertical edge to swing upwardly 50 to an open position, said holding means comprising a door engaging member having a carrying sleeve, and a vertically disposed rod slidably surrounded by said sleeve to permit movement of said member to either 55 of its two operative positions, the ends of said rod being directed laterally for anchorage to a fixed support.

3. A grain car door pivotally mounted at one lower corner, the pivotal mounting of

said door having a horizontal pivot and a 60 vertical pivot to permit the door to be opened by movement in either of two directions, a chain connected with said door and a hook cooperable with said chain for holding the door in an inclined partly opened 65 position, said chain and hook being also operative to support the weight of the door when the latter is horizontally swung to open position and then slightly raised.

4. Means for controlling the closing movement of a downwardly closable door, said means comprising a track above the door, a 70 brake lever having a guide slidable along the track and adapted to frictionally bind against the latter when the lever is moved 75 to predetermined angular relation with respect to the track, and connecting means between said lever and the door.

5. Means for controlling the closing movement of a downwardly closing door, said 80 means comprising an inclined rod stationarily mounted above the normal closed position of the door and laterally of such position, a brake lever having a guide slidable along said rod and adapted to frictionally 85 bind against the same when the lever is angled into predetermined relation with respect to the rod, and a chain connecting said lever with the door.

6. Holding and controlling means for a door pivotally mounted near one vertical edge for upward swinging to open position, said means comprising a vertical rod substantially in line with said edge of the door and having its ends laterally offset for anchorage to the door frame, a sleeve slidable along said rod and having a laterally projecting door-holding portion to engage the upper edge of the door when the latter is in either open or closed position, a second rod projecting laterally from the upper portion of the first named rod and having its outer end anchored, a brake lever having a guide slidable along said second rod and adapted to bind frictionally against the same when said lever is moved into predetermined angular relation with this rod, and a flexible connection between said lever and the door.

7. A structure specified in claim 6; said 100 anchored end of said second rod being bent to form a hook to receive the door when the latter stands in its upwardly swung or open position.

In testimony whereof I have hereunto 110 affixed my signature.

CARL AUGUST JOHANSON.
